tion of Illinois

Application March 19, 1948, Serial No. 15,941

3 Claims. (Cl. 123—41.38)

1 This invention is concerned with the cooling of pistons and is particularly exemplified by novel features of construction and arrangement to enable a more effective cooling of pistons and the like.

A particularly important objective of the present invention is found in the novel and improved characteristics of piston construction and arrangement of cooperating parts to enable a more rapid and perfect transfer of heat from the piston to a cooling medium supplied thereto.

More specifically, it is an object hereof to provide a piston constructed in such a way that the interior areas of the piston are characteristically divided into a head end and a skirt end chamber, and to supply and control the flow or circulation of the cooling medium such that it can absorb a maximum of heat in the head end chamber, then move to the skirt end chamber and eventually be discharged, the control of the circulation of the cooling medium being accomplished in part through the aid of the physical arrangement of the piston parts and in part by the forces to which the cooling medium is subjected during piston operation.

In accordance with the above stated object, the preferred piston construction embodies the important features of supplying the cooling medium to the head end chamber, there causing a great degree of turbulence and cross flow more perfectly to bring the cooling medium into intimate contact with the heated surfaces for heat transfer therebetween, controlling the rate of discharge or removal of the cooling medium toward the skirt end chamber such that the head chamber is maintained substantially one-half full of the cooling medium, and causing a complete change of cooling medium in the piston by regulating the final discharge from the skirt chamber such that the residual body of cooling medium therein will not adversely oppose the flow of medium out of the head chamber under the influences of forces to which the cooling medium is subjected during piston operation.

Further objects and attendant advantages will appear from the following description relating to a presently preferred embodiment of the invention as the same is illustrated in the accompanying drawing, wherein:

Fig. 1 is a longitudinal, sectional elevational view of the piston assembly in which the important characteristics of structure are shown:

Fig. 2 is a top view in section of the present piston, the view being taken at line 2—2 in Fig. 1, and

2 Fig. 3 is an enlarged and fragmentary sectional view of a typical flow controlling orifice opening between the respective piston chambers, the view being taken at line 3—3 in Fig. 2.

5 In the drawing, the piston 10 best illustrating the characteristics of construction and arrangement, is seen to include a hollow, cylindrical body having a skirt wall 11 integrally formed with a crown wall 12 of semi-spherical configuration. 10 The skirt wall 11 is formed with an upper thickened band or wall zone 13 in the outer surface of which suitable grooves are formed to receive the piston rings, and a lower, thickened band or wall zone 14 adjacent the open end thereof and 15 in the outer surface of which grooves are formed to receive other piston rings. The crown wall 12 of the piston body is provided at its under side with a plurality of depending elements arranged in inner and outer groups or series 15 and 16 respectively. 20 These struts are each arcuately shaped, and the groups thereof are substantially concentrically related and extend parallel with the longitudinal axis of the piston 10.

More specifically, the inner series of arcuate 25 elements 15 are arranged in circumferentially spaced relation to define a central crown pocket 17 which opens at the slot-like ports 18 (four such ports being indicated in Fig. 2) to the annular space 19 defined by the outer series of circumferentially spaced elements 16. The disposition of elements 16 is such that an outer annular cavity 20 is formed between each thereof and the upper adjacent zone of the skirt wall 11. The elements 16 also provide slot-like ports 21 30 therebetween which are staggered relative to the ports 18 between the inner series of elements 15. In the casting of this piston body, the outer elements 16 are each connected with the thickened skirt wall zone 13 by means of a boss 22, these 35 bosses being open across the top so that the outer annular cavity 20 is uninterrupted in its upper peripheral zone adjacent the skirt wall 11 and the under side of the crown wall 12.

The present piston assembly (Fig. 1) also includes an insert member 25 formed to provide an upper flat face 26 bounded by the flange 27 which is adapted to engage the skirt 11 at the annular, shouldered seat 28 machined into the thickened wall zone 13. The lower end of the member 25 45 is characterized by the flange 29 adapted to have a close sliding fit with the inner surface of the thickened skirt wall zone 14. Intermediate the ends of the member 25, suitably formed and spaced bearing boss formations 30 are provided 50 to receive the wrist pin 31. In turn, the pin 31

engages in the bearing bore of the upper end 32 of the usual connecting rod member 33. As shown in Fig. 1, the insert member 25 is spaced from the skirt wall 11 to define an annular skirt chamber 35 which is closed, to the extent hereinafter to be described, by the flanges 27 and 29.

The assembly of the several parts of the present piston is believed obvious, when it is understood that the securing studs 37 threadedly engage in the upper bosses 22 of the body, extend axially through a drilled bore in longitudinal bosses 39 of the insert member 25 and are engaged by nuts 38 at their free ends. Further, and before assembly, each of the struts 15 and 16 is machined across its free end to a common plane which is coplanar with the seat 28 in thickened zone 13 of the skirt wall 11. A characteristic of this piston assembly is exemplified by the provision of a crown or head end chamber above the flat end face 26 of the insert member 25, and the skirt end chamber 35 below this face 26.

Cooling medium for the piston 10 is supplied from the crankshaft lubricating system (not shown) through the bore 40 in the connecting rod 33, and the annular groove 41 in the rod end portion 32 to the outlet passage 42 at the upper zone thereof. The cooling medium or coolant passes into the central crown cavity 17 by way of the enlarged port 43 at the face 26 of member 25. An annular sealing ring 44 is adapted to bear upon the rod head 32 under the loading of a suitable spring 45 and prevent leakage of the coolant away from the piston crown chamber.

The coolant (engine oil in this case) entering the crown chamber in the zone of the central cavity 17 is under pressure and thus possesses a velocity component which causes its rapid flow outwardly of this cavity 17 through each of the several slot-like ports 18 between the inner series of elements 15. In treating this pressurized flow of coolant which reaches the central cavity 17, it is highly important that no stratified flow trends develop in the crown chamber which could cause an inequitable heat absorbing contact of the coolant with the piston crown areas which receive heat from the combustion or firing side of the crown 12. This hazard is effectively overcome by arranging the ports 18 of the inner series of elements 15 in off-set or staggered relation relative to the ports 21 of the outer series of elements 16. Thus, the coolant is compelled to leave the central cavity 17 in a plurality of paths or streams, and in like manner is compelled to leave the annular cavity 19 in a plurality of paths or streams which are not directly in the line of the first created flow paths. The coolant must then traverse a course to the outer annular cavity 20 which requires a change in direction of flow. Hence, the coolant in the crown chamber is forced to contact substantially all of the heated surfaces of the piston crown and depending elements, and in the process a beneficial degree of turbulence is established which increases the rate of heat transfer from the metallic body to the fluid coolant.

The body of cooling fluid supplied to the crown chamber of the piston is discharged to the annular skirt chamber 35 by way of a plurality (four being shown in Fig. 2) of restricted orifices 41. These orifices or transfer ports 41 are located in spaced pairs, each pair being in diametrically opposed relation, and in the upper peripheral flange 27 of the insert member 25 in the zone of the outer annular crown cavity 20 between adjacent stud receiving bosses 22. The

coolant passing to the skirt chamber by way of these orifices 41 is eventually discharged to the crankcase (not shown) by a suitable discharge opening or spitter passage 48 provided in the lower flange 29 of the insert member (Fig. 1).

The cooling of a piston having the above described physical characteristics is predicated upon the important principles that the coolant admitted to the crown chamber should be allowed to remain in contact with the hot metal surfaces sufficiently long to absorb a maximum of heat, that the rate of heat absorption can be materially increased by the turbulence of the coolant and its rapid flow over the heated surfaces, that the heated coolant should be discharged as quickly as possible with a minimum of impedance to its flow, and that the coolant should be completely changed as frequently as possible. In keeping with these principles, the present piston construction is so designed that a body of coolant is maintained in the crown chamber equal approximately to one-half the crown chamber volume. Maintaining this volume of coolant in the crown chamber is accomplished by selecting an orifice diameter which approximately balances the rate of flow outwardly of these orifices with the rate of supply of fresh coolant at port 43, and by forming each orifice (Fig. 3) with a rounded lip zone 49 facing the crown chamber and a relatively sharp lip 50 at its opposite end so that the flow toward the skirt chamber 35 is relatively less retarded than flow in the opposite direction. It is desired that a portion of the coolant flowing into the skirt chamber 35 return to the crown chamber under inertia forces of piston movement to enhance the turbulent character of coolant movement in the latter chamber. But at the same time more coolant must be moving away from this crown chamber than is returned to it to maintain the desired volume of coolant therein, and to balance the volume of fresh incoming coolant. Further assistance in respect of maintaining the volume of coolant in the crown chamber is attained by proper selection of the size of the final discharge or spitter port 48 in the lower flange 29 of the member 25. While only a single spitter port 48 has been indicated, it is possible to provide a plurality of such ports. In either case, the effective area of the port, or ports, should be calculated on the basis that coolant to a depth of approximately one inch in the skirt chamber when the piston is on crank end center is most desirable. This quantity of coolant will reduce excessive reverse flow of coolant toward the crown chamber when the piston reaches its head end center where the inertia forces on the coolant attain a maximum.

In operating a piston of this character, there will be periods in the cycle of motion when the coolant flows outwardly from the central cavity 17, other periods when this flow is reversed, and still other periods when the flow is either of these combined with a flow into or out of the crown chamber. Thus the coolant is made to attain a high degree of turbulence in the zone of highest temperature and more perfectly contact the hot metal surfaces with a marked increase in the rate of heat absorption. The elements 15 and 16 in this crown chamber further control the coolant flow, increase its equitable distribution throughout the chamber area, and generally act and perform the function of baffles.

The foregoing description has been given in connection with a presently preferred piston as-

sembly, however it is not the purpose to limit the scope of the invention precisely to that which has been disclosed, as it is entirely possible to have substantially equivalent structural features for attaining a similar cooling result without departing from the spirit and full intent of the claims hereunto appended.

What is claimed is:

1. In a piston of the character described, a piston body having a crown and a skirt, a member disposed in said body and cooperating with the latter to define a chamber adjacent the crown and a chamber between the body skirt and member, said member having a plurality of ports opening between said crown and skirt chambers and a passage opening from the skirt chamber to the exterior of the piston, and a connecting rod operatively connected with said member and provided with coolant feed passages opening to said crown chamber, said ports in said member being formed with a curved lip at the crown chamber end thereof to permit the passage of more coolant from the crown chamber than is induced to reenter from the skirt chamber due to forces to which the coolant is subject during piston operation, and the passage opening from said skirt chamber being of such area as to limit the volume of coolant collecting in the latter chamber.

2. A piston comprising a body having an integrally formed crown and skirt, a member positionable in said body and cooperating therewith to define a crown chamber and a skirt chamber, said member having a coolant inlet port opening centrally of the crown chamber, a plurality of spaced orifices opening between said chambers, and a spitter passage opening from said skirt chamber, and a plurality of baffle means arranged in said crown chamber to define intercommunicating crown cavities through which coolant flows, each of said orifices having a curved lip at the crown chamber and a relatively sharp lip at the skirt chamber, and the combined areas of said orifices being chosen such that the flow of coolant into and out of said crown chamber is regulated to maintain a coolant volume therein

of substantially one-half the crown chamber volume, whereby the inertia forces imposed on the coolant during piston operation will result in a high velocity and turbulent movement of the coolant within said crown chamber and through and between the cavities thereof.

3. In a piston of the character described, a body having crown and skirt portions, a member positionable in said body to cooperate therewith in defining a crown chamber and a skirt chamber, baffle means arranged in said crown chamber and adapted to define a plurality of interconnected passages between the central and peripheral zones of the crown chamber, said member being formed to provide a coolant inlet port for the crown chamber, transfer ports opening between said chambers, and an outlet port opening from the skirt chamber, and means operatively associated with said member for supplying coolant to said inlet port for admission to the crown chamber, said transfer ports being formed with a rounded lip at the crown chamber end and a relatively sharp lip at the skirt chamber end whereby the flow of coolant from the crown chamber toward the skirt chamber is relatively less restricted than in the reverse direction of flow, and said outlet port being of a size to discharge the coolant from the skirt chamber at a rate less than that which would maintain the skirt chamber substantially empty during piston operation.
